UNITED STATES PATENT OFFICE.

ABRAHAM BARCHOFF, OF NEW YORK, N. Y.

TRAY AND METHOD OF MAKING SAME.

Application filed October 28, 1924. Serial No. 746,274.

The present invention relates generally to trays, plates, platters, or the like, which are to have supporting feet, such as ash-trays, bread-trays, cake-plates, sandwich-trays, meat-platters or other similar articles. As an example of the embodiment of my invention in one form, and the proper method of applying it, a meat-platter of a well and tree configuration in the base and having supporting feet will be used. Heretofore the manufacture of meat-platters, either with or without supporting feet, has been a long expensive process, and particularly so if supporting feet were desired, as these had to be made separately. After making the feet it was necessary to secure them to the platter separately, either by soldering (as was usually done), or by riveting or in some other manner. Supporting feet are very desirable as they raise the body of the hot tray, thus protecting the surface of the furniture, and preventing the table-cloth, doilies, etc. from sticking to and marking the furniture, as well as adding grace and symmetry to the article, in addition to giving greater convenience in handling by permitting the fingers to be readily slipped under in picking up the tray.

One of the objects of my invention is to provide a simple and cheap method by which a meat-platter employing the well and tree configuration, for example, may be made, so that a platter or tray so produced will not only be simple and inexpensive to produce, but will be neat, graceful, and attractive in appearance.

Another object is to provide a tray or platter which has supporting feet integral with the main body, thus eliminating the possibility of the feet being knocked off in use, or melting off if the platter should be left inadvertently on the hot stove or other hot surface. Furthermore these integral supporting feet are provided with practically no increase in the cost of producing the article.

A further object is to provide a meat-platter which readily adapts itself to quantity production, with consequent lower unit cost, as the processes of manufacture are very simple step-by-step ones, not requiring special skilled labor.

A further object is the production of a tray of the character described herein, which will be simple in construction, cheap to manufacture, neat and attractive in appearance.

With these and other objects in view, to be

more fully set forth hereinafter, the invention consists in the novel construction, which will be exemplified in the construction herein described in the following specification and illustrated in the accompanying drawings.

The invention will first be described in connection with the accompanying drawings, wherein similar reference characters are used to designate corresponding parts throughout the several views, and more specifically defined and indicated in the appended claim.

Attention is directed to the drawings in which—

Fig. 1 is a plan view of my improved tray formed in the original sheet or blank;

Fig. 2 is a central sectional elevation, taken on the line 2—2, Fig. 1, looking in the direction of the arrows;

Fig. 3 is a detailed view showing a step in the manufacture;

Fig. 4 is a detailed view showing another step; and

Fig. 5 is a detailed view on line 5—5 of Fig. 1 showing a portion of the completed tray with an integral supporting foot.

A sheet or blank of suitable material 1, brass for example, is deformed in one operation or stroke of a pair of forming dies (not shown) as shown in Fig. 1. These forming dies are so patterned as to produce in one stroke the tray proper 5 (Figs. 2 to 5) as well as the gravy well 2, the gravy "tree" 3 and the four deeper depressions 4 which form the supporting feet. The gravy "tree" may be of the construction somewhat resembling the bed of a river, in that the gravy, meat juices etc. will drain down into the well portion 2 where they may be readily removed, as will be well understood.

The second operation is the cutting out of the contour of the formed platter along the dotted line 6, Fig. 1, by the action of suitable cutting or punching out dies, thus providing a formed platter with a plain horizontal rim 6', Fig. 2.

The result of the third operation is illustrated by Fig. 3, in which two forming dies (not shown) in one stroke have deformed rim 6', around the entire periphery of the tray, into stepped-up portions 7 and 8, as well as deforming the extreme edge of the rim 6 into depending right angled flange 9.

The fourth operation being merely the crimping in of flange 9 to form the crimped rim 10 of Figs. 4 and 5, by action of crimp-

ing dies (not shown), or any other suitable means, as will be readily understood.

The manufactured tray may now be finished off by silver-plating, or treated in any other desired manner, in the usual way. If desired, the crimped rim 10 may be filled with solder, or other suitable filling material, in order to present a smoother, more uniform and sanitary surface; also for the same purpose supporting feet 4 may be filled in up to the level of the bottom of tree 3 at that point.

By forming a tray in the manner hereinbefore described, I produce a tray in which the feet or supporting members are made as an integral part of the whole structure and no soldering or riveting is required to fasten the feet, as was the practice heretofore, and there is no possibility of the feet being knocked off or melted. I wish to call attention to the fact that supporting feet 4 are so positioned as to form part of the design or configuration in the tray. Any design could be utilized and the same result accomplished so that the depressions 4 will act as the support members or feet.

In accordance with the provisions of the patent statutes, I have described my invention together with the construction which I now consider to represent the best embodiment thereof, but I desire it understood that

my invention is not confined to the particular form shown and described, the same being merely illustrative, and that the invention can be carried out in other ways without departing from the spirit of my invention, and, therefore, I claim broadly the right to employ all equivalent instrumentalities coming within the scope of the appended claims, and by means of which objects of my invention are attained, and new results accomplished, as herein set forth, as it is obvious that the particular embodiments herein shown and described are only some of many that can be employed to attain these objects and accomplish these results.

Having now described my invention, what I claim and desire to secure by Letters Patent is:

A sheet metal tray having its upper surface indented to form a median channel with branches extending laterally to both sides of both ends thereof, each branch having at its extremity a coniform additional depression, said depressions in said upper surface producing embossments which serve as supports on the lower surface of said tray.

This specification signed this 18th day of October, 1924.

ABRAHAM BARCHOFF.
